UNITED STATES PATENT OFFICE.

ARTHUR D. BACK, OF JUNEAU, DISTRICT OF ALASKA.

BAG-HOLDER.

1,038,474.

Specification of Letters Patent. Patented Sept. 10, 1912.

Application filed March 5, 1912. Serial No. 681,676.

REISSUED

To all whom it may concern:

Be it known that I, ARTHUR D. BACK, a citizen of the United States, residing at Juneau, in the first division of the District 5 of Alaska, have invented certain new and useful Improvements in Bag-Holders, of which the following is a specification.

My invention relates to an improvement in bag holders, and the object is to provide 10 a simple device for holding paper bags or sacks in convenient position to be quickly and easily removed by the merchant while serving a customer; and a further object is to provide a holder which may be easily replenished with more bags or sacks.

With these objects in view, this invention consists in certain novel features of construction and combinations of parts which will be hereinafter described more fully and 20 set forth in my claim.

I have illustrated my invention in two forms, and in the accompanying drawings, Figure 1 illustrates a perspective view of one form of the invention, Fig. 2 is a side 25 view of the same showing bags in position, Fig. 3 is a rear view, Fig. 4 is a perspective view of the other illustrated form of my invention, and Figs. 5 and 6 are side and plan views respectively of the latter form of 30 bag holder.

A, is the base, preferably made of a sheet of metal recessed at the forward end to form a narrow, upturned lip 15, the function of which will be hereinafter explained. A 35 frame-work of wire is erected on the base, and comprises two long uprights 16, 16, connected by a cross-bar 17 at the top, which has an eyelet 18 in the center whereby the holder may be suspended on a nail or hook, 40 two shorter uprights 19, 19, at the front, and two side-bars 20, 20, connecting the upper ends of the short uprights with the longer uprights 16, 16, and a roller 21 extends across from one of the shorter uprights to 45 the other in front of the holder. A U-shaped spring 22 extends downwardly from the cross-bar 17 and presses forwardly toward the roller and has a shield or follower 23 slidably connected therewith and 50 with the side-bars 20, 20. A curved catch 24 is centrally secured to a pivoted cross-bar

25, having counterweights 26, 26, on its ends in position to automatically engage the spring when the latter and the shield or follower are forced back when it is desired to 55 replenish the holder. When thus adjusted, the space between the shield and the roller and the side-bars 20, 20, is filled with bags or sacks after which the weights are lifted and the spring is allowed to press the shield 60 or follower forward against the bags or sacks, holding them compressed between it and the roller and the lip 15, the function of which latter is to cause the upper edge 27 of the folded bottom of the outermost bag 65 to extend outwardly where it is convenient for the operator to grasp it when he desires to remove a bag or sack from the holder, as clearly shown in Fig. 2. This greatly facilitates the operation of grasping and removing 70 a bag, and the roller also reduces the friction which would otherwise be caused by the pressure exerted by the springs upon the bags.

In the form shown in Figs. 4, 5, and 6, A' 75 is the back; B, the front; 1, is the base, all made preferably of thin wood; and 2, indicates a slot, and 4, a notch at the front through which the bags are removed; and 5, 5, are the cross-bars connecting front and back; 7, 7, indicate the spring; and 8, 8, the coils; and 6, is the follower or shield which compresses the bags or sacks and holds them in their upright position as shown in Fig. 5. Slide 9 operating through guides 10, 10, has 85 hooks 11, 11, to engage the spring 7, 7, when the spring is moved rearward and compressed for clearing the space to replenish the holder.

The device is supported by nails or screws 90 inserted through the hooks or eyelets 12, 12, at the top of the upper edge of the back A'.

From the foregoing, it will be seen that I have provided a very simple and inexpensive article of manufacture for holding 95 bags in convenient place where they may be quickly removed, which is a desideratum as much time is ordinarily lost by the merchant in manipulating these bags which by means of this device is reduced to a mini- 100 mum.

Having fully described my invention,

what I claim as new and desire to secure by Letters Patent, is:—

A bag-holder comprising a base, back, front, and side-bars, a shield or follower loosely and slidably mounted on two of the side-bars, and a spring secured to the back and slidably connected with the shield or follower.

In testimony whereof I affix my signature, in the presence of two witnesses.

ARTHUR D. BACK.

Witnesses:

JOHN B. MARSHALL,
ROYAL A. GUNNISON.
